ROLLER TYPE PAINT APPLICATOR

Albert W. Schaefer, Los Angeles, Calif.

Application September 20, 1948, Serial No. 50,217

2 Claims. (Cl. 15—230)

1

This invention relates to a paint applicator of the roller type. More particularly, it relates to a roller type paint applicator adapted to apply paint to corners or other areas of difficult access.

Paint applicators of the roller type comprising a roller and a nap or other suitable paint absorbent material secured to the roller, are useful as providing an easy means of applying paint. Also, such paint applicators can be adapted to stippling or applying a smooth coat and they are safely used by inexperienced operators.

Such rollers, however, as heretofore designed are disadvantageous in that it is difficult to apply paint to corners and other areas of difficult access.

It is an object of the present invention to provide a roller type paint applicator which is adapted to apply paint to corners and other areas of difficult access.

It is a further object of the invention to provide a roller type applicator adapted to apply paint to corners, which is of simple design and inexpensive and can be carried in a painting kit as a useful accessory.

It is a still further object of the invention to provide a paint applicator of the roller type which is applicable to applying paint in corners and the like and which has a removable napped sleeve such that it can be easily removed and replaced by a different sleeve.

These and other objects of the invention will be apparent from the ensuing description and the appended claims.

One form which the invention may assume is exemplified in the following description and illustrated by way of example in the accompanying drawings, in which:

Fig. 1 is a view, partly in elevation and partly in section, showing the paint applicator of the invention.

Fig. 2 is a perspective view of the removable napped sleeve used with the applicator, showing the manner in which it is formed.

Fig. 3 is a perspective view illustrating how the roller may be used to apply paint to a corner area.

Referring now to the drawings, there is provided a bent handle 1 having a hand grip 2 at one end and a shaft portion 3 at the other end thereof. The shaft 3 is of smaller diameter than the adjacent handle portion to provide a shoulder 4, and the outer end of the shaft is threaded at 5 as shown. Mounted on the shaft and secured thereto by means of washers 10 and a nut 11 is a disc-shaped roller 12, which may be made of any

suitable material but is advantageously made of transparent, plastic material such as lucite. The roller 12 is provided with a transverse bore 13 of a diameter to form a close fit with the shaft 3 but to allow the roller to rotate freely thereon. The relatively narrow peripheral surface of the roller is defined by two outwardly converging frusto-conical side surfaces 15 and is provided with a peripheral groove 14.

10 A removable sleeve 16 is provided having a core or backing 17 of any suitable flexible material, such as leather, and with an outer nap material 18 of wool or other suitable paint absorbent material. The core 17 may be provided sepa-

15 rately, cut to strip form and provided with a separate nap material 18, which is affixed to the core in any suitable manner, as by an adhesive. Preferably, however, the sleeve 16 is in the form of an animal pelt, such as a sheep pelt, cut to strip

20 form, the core 17 being provided by the hide of the animal and the nap material 18 by its hair or wool. The sleeve 16, as shown, is considerably wider than the thickness of the roller 12. The ends of the sleeve are brought together to form a

25 seam at 19 and the adjacent edges are secured together by any suitable means, such as staples 20, the staples being inserted from the interior of the core so that their free ends are located on the exterior surface of the core. Seating staples 21 are also provided, as shown, being disposed circumferentially about half way between the side edges of the sleeve and being inserted in the same manner as the seam staples 20.

The sleeve thus provided is readily mounted on the roller 12 and, as will be seen from Fig. 1, the seating staples 21 are seated in the peripheral groove 14, thus serving to retain the sleeve in place but, nevertheless, allowing ready removal of the same as by inserting a finger and pulling the sleeve off of the roller.

40 As shown in Fig. 3, the sleeve is highly flexible and assumes the shape of an inside corner. This deformation of the sleeve to conform to the angle of a corner is rendered possible because of the relatively great width of the sleeve, the relatively small width of the roller and the tapered edge of the roller. Thus, the sleeve assumes a 90° angle with a sharp corner or apex to the angle.

45 A paint applicator is thus provided which is simple in design, inexpensive to manufacture, easy to assemble and disassemble, and efficient for the purposes described. The sleeve itself is advantageous for the same reasons and because it is easily mounted and dismounted.

50 While I have shown the preferred form of my

3

invention, it is to be understood that various changes may be made in its construction by those skilled in the art without departing from the spirit of the invention as defined in the appended claims.

Having thus described my invention, what I claim and desire to secure by Letters Patent is:

1. A roller type paint applicator comprising a handle portion, a shaft mounted on said handle, said shaft having a right-angle bend at its free end, a disc rotatably mounted on the free end of the shaft, said disc having frusto-conical side surfaces converging to a relatively narrow peripheral surface, a groove formed in the peripheral surface of said disc, a flexible cylindrical napped sleeve fitting on said disc and having a width substantially greater than said disc, said sleeve having inwardly protruding members on its interior disposed in the groove in the disc.

2. A roller type paint applicator comprising a handle portion, a shaft mounted on said handle portion, the free end of said shaft being bent right-angularly, a disc rotatably mounted on the free end of said shaft, said disc having its side surfaces converging to a relatively narrow peripheral surface extending around the disc, a groove formed in the peripheral surface of said disc, a flexible cylindrical napped sleeve having inwardly protruding members on its inner surface, said

5 sleeve being mounted on said disc and having the inwardly protruding members thereof seated in said groove and precluding endwise or axial movement of said sleeve, the end portions of said flexible applicator sleeve extending beyond said peripheral surface of said disc and adapted to be bent back upon said disc as paint is applied to a corner to conform to the walls forming the corner.
